UNITED STATES PATENT OFFICE.

CHARLES BOOZE, OF BUFFALO, NEW YORK, ASSIGNOR TO M. H. BIRGE & SONS,
OF SAME PLACE.

DESIGN FOR WALL-PAPER.

SPECIFICATION forming part of Design No. 21,916, dated October 25, 1892.

Application filed September 29, 1892. Serial No. 447,337. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

The leading feature of my design consists of sprays of leaves and flowers of the verbena, combined with grass-like sprays bearing small star-shaped flowers, as represented in the accompanying drawing. The combined sprays or twigs of the verbena leaves and flowers and the grass-like sprays are arranged in ir-

regular order over the surface of the paper at suitable distances apart and separate sprigs of grass are arranged in the space between the combined sprigs of the verbena-flower. 20

The design is printed upon tinted paper of any desired color.

What I claim is—

The design for wall-paper herein shown and described. 25

Witness my hand this 24th day of September, 1892.

CHARLES BOOZE.
